(57) **CLAIM**

The ornamental design for a relocatable support surface, as shown and described.

DESCRIPTION

FIG. 1 is a perspective view of a relocatable support surface for a media player (including, but not limited to, laptop and tablet computers, e.g., the iPad (trademark of Apple, Inc.).

FIG. 2 is a front elevation view thereof;

FIG. 3 is a back elevation view thereof;

FIG. 4 is a top plan view thereof;

FIG. 5 is a bottom plan view thereof;

FIG. 6 is a right side elevation view thereof;

FIG. 7 is a left side elevation view thereof;

FIG. 8 is a perspective view thereof, but showing environment in broken lines;

FIG. 9 is a perspective view thereof, but showing another environment in broken lines; and,

FIG. 10 a perspective view thereof, but showing another environment in broken lines.

The broken lines shown in the drawings represent environmental structures that form no part of the claimed design.
